(57) **CLAIM**

The ornamental design for a universal slide mount, as shown and described.

DESCRIPTION

FIG. 1 is a front, top, left side perspective view of a universal slide mount showing the present design;

FIG. 2 is a rear, top, left side perspective view thereof;

FIG. 3 is a top view thereof;

FIG. 4 is a left side view, right side view being a mirror image thereof; and,

FIG. 5 is a bottom view thereof.

The broken line showing of universal slide mount is for the purpose of illustrating portions of the article that form no part of the claimed design.
